Attorneys

UNITED STATES PATENT OFFICE

2,379,619

WRINGER

Earl L. Baker, Washington, D. C.

Application March 1, 1944, Serial No. 524,608

3 Claims.

(Cl. 15—262)

This invention relates to wringers for removing liquid from fabric and is especially adapted for wringing mops and like devices, and has for the primary object the provision of a portable device of this character which will render the wringing of mops and similar devices much quicker and easier for a person and with less danger of tearing or otherwise damaging the fabric of the mop.

Another object of this invention is the provision of a device of the above stated character in which the mop fabric may be easily arranged and a pressure varied thereon in accordance with the desire of the person using the device along with a rotary action for feeding the mop fabric from the device as it is squeezed to efficiently remove the fluid therefrom.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawing, in which

Figure 1 is a side elevation illustrating a wringer constructed in accordance with my invention, and showing the device in an operative position of wringing the fabric of a mop.

Figure 2 is a top plan view illustrating the device.

Figure 3 is a side elevation illustrating the device in an inoperative position, ready to receive the fabric of a mop.

Figure 4 is a front elevation illustrating the device.

Referring in detail to the drawing, the numeral 5 indicates a base which may be of any desired shape preferably rectangular, as shown in Figure 2, and has secured thereto vertically arranged supports 6 disposed opposite to each other and provided with slots 7 and 8 opening outwardly through the opposite ends thereof. The upper slots 7 are arranged uppermost and provide journals for pintles 9 of a roller 10. A pivot rod 11 extends through the lower slots 8 and is secured to swingable members 12 shaped similarly to the supports 6.

The upper ends of the members 12 are apertured to receive a shaft 13 of a roller 14 adapted to coast with the roller 10 in squeezing liquid from fabric. One end of the shaft 13 is bent to form a crank handle 15. The supports 6 and the members 12 have their lower ends enlarged and the lower ends of the supports are firmly secured

to the base 5 as at 6' while the lower ends of the members 12 may at times rest flatly on the base or at other times assume a position with corners thereof resting on the base, and when in this latter position the members 12 will be inclined laterally of the supports and thus positioning the roller 14 a considerable distance away from the roller 10 so that a mop fabric as shown in Figure 1 may be laid across the roller 10 with the latter 15 adjacent the mop head. The members 12 may then be swung manually into parallel relation with the uprights or supports 6 and the shaft 13 permitted to enter the slots 7 and move downwardly therein until the roller 14 rests upon the mop fabric.

A treadle 16 disposed over a portion of the base 5 is secured to the rod 11 so that the operator may place the foot thereon and press downwardly on the rod 11 bringing a squeezing action on the mop fabric by the roller 14 pressing in the direction of the roller 10. With the weight still maintained on the treadle 16, the operator rotates the crank handle 15 which brings about feeding of the mop fabric from between the rollers with a squeezing action removing therefrom the liquid and at the same time freeing the mop fabric ready to be used in a mopping operation.

A drain shelf 17 is supported at an inclination by the supports 6 directly below the roller 10 so that the liquid flowing from the mop fabric may be caught and directed into a receptacle of any suitable kind arranged on the base 5 and directly below the shelf 17. After the wringing operation of the mop fabric has been completed, the operator removes the foot from the treadle and lifts upwardly on the roller 14 or the crank handle 15 thereof and swings the members 12 laterally of the supports to assume the angular position as shown in Figure 3, whence the device 35 is ready again to receive a mop fabric for wringing.

From the foregoing description, taken in connection with the accompanying drawing, it will be seen that a very simple, durable and compact wringer has been provided which can be easily moved from place to place and used wherever desired and the construction thereof is such that the mop fabric can be easily arranged in position of receiving a wringing action thereon. Further, it will be noted that the pressure on the mop fabric can be varied in accordance with the desire of the operator and that during the pressure on the mop fabric the rollers may be conveniently rotated to feed the mop fabric from the rollers with the desired pressure thereon. A device of this

construction can be made from any material suitable for the purpose.

While I have shown and described the preferred embodiment of my invention, it will be understood that minor changes in construction, combination and arrangement of parts may be made without departing from the spirit and scope of the invention claimed.

Having thus described my invention, what I claim is:

1. In a wringer, a substantially rigid upright supporting structure including spaced-apart parallel vertical supports each having a longitudinal slot in its upper end portion, each slot being open at its upper end, a roller journaled by pintles at its opposite ends in the lower ends of said slots, a second roller arranged and adapted to coact with the first-mentioned roller in squeezing fabric placed between the rollers, said second-mentioned roller having pintles movable into and out of the open upper ends of slots of said supports and having means for the rotation of said second-mentioned roller, a mounting for said second-mentioned roller pivotally and longitudinally slidably connected to the lower end portion of each of said supports for pivotal and sliding movement thereon, and means for forcibly moving said mounting to move said second roller downwardly so as to cause compression of the fabric interposed between the carried roller and the opposed stationarily supported roller.

2. In a wringer, a base, spaced-apart parallel uprights secured to said base and each upright having upper and lower longitudinal slots therein, each of said upper slots being open at its top, said uprights being stationarily and rigidly supported at their lower ends on said base, a roller journaled by pintles at its opposite ends in the lower ends of the upper slots of said uprights, a second roller having pintles movable into and out of the open upper ends of said upper slots above said first-mentioned roller so as to coact with said first-mentioned roller in squeezing a fabric placed therebetween, a crank handle connected to the second-mentioned roller for forcible rota-

tion of the same, mounting means for said second roller including a rod extending through the lower slots in said uprights, said mounting means being thereby pivotally and slidably connected to said uprights and having the second-mentioned roller journaled thereon and, through the medium of said rod, the pintles of said second-mentioned roller being also supportedly but releasably journaled in said upper slots in said uprights, and means for forcibly operating said pivotal and slideable mounting means physically to effect compression by and under control of the operator upon material interposed between said first and said second-mentioned rollers.

3. In a wringer, a base, spaced-apart parallel uprights secured stationarily and rigidly to said base and each upright having upper and lower longitudinal slots therein, each of said upper slots being open at its top, a roller journaled at its ends by pintles in the inner ends of the upper slots of said uprights, a second roller movable into and out of the upper open-ended slots above said first-mentioned roller so as to coact with the first-mentioned roller in squeezing a fabric placed therebetween, a crank handle connected to the second-mentioned roller for forcible rotation of the same, mounting means for said second roller including a rod extending through the lower slots in said uprights, said mounting means being thereby pivotally and slidably connected to said uprights and having the second-mentioned roller journaled thereon, and, through the medium of said rod, the pintles of said second-mentioned roller being also supportedly and releasably journaled in said upper slots of said uprights, a treadle secured to said rod so that physical pressure-creating force may be applied to said second-mentioned roller under control and operation of and by an operator when said second-mentioned roller is coacting with the first-mentioned roller in squeezing fabric placed therebetween, and a drain board carried by the uprights below said first-mentioned roller and inclining in a downward direction toward the base.

EARL L. BAKER.
